Primary Examiner — David Muller*(74) Attorney, Agent, or Firm* — Chapman and Cutler LLP(57) **CLAIM**

The ornamental design for a nozzle cap for syringe, as shown and described.

DESCRIPTION

FIG. 1 is a front perspective view of a nozzle cap for syringe showing my new design;

FIG. 2 is a front perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof;

FIG. 8 is a left side elevational view thereof;

FIG. 9 is a sectional view thereof taken along line 9-9 of FIG. 3;

FIG. 10 is a perspective view thereof; and,

FIG. 11 is a perspective view thereof.

The broken lines are for the purpose of illustrating environmental structure only and form no part of the claimed design.
